UNITED STATES PATENT OFFICE

FRITJOF FRELIN, OF PHILLIPSBURG, NEW JERSEY, ASSIGNOR TO INGERSOLL-RAND COMPANY, OF JERSEY CITY, NEW JERSEY, A CORPORATION OF NEW JERSEY

FUEL PUMP

Application filed January 7, 1932. Serial No. 535,290.

This invention relates to pumps, but more particularly to a fuel pump of the type employed for pumping fuel under pressure to the cylinder or cylinders of an internal combustion engine.

One object of the invention is to enable the excess fuel under pressure to be readily by-passed from the pumping chamber to a source of fuel supply.

Another object is to avoid subjecting the by-pass valve and its actuating mechanism constantly to the discharge pressure of the pump.

Still another object is to adequately seal the by-pass valve mechanism and thus prevent leakage of fuel to the exterior of the casing.

Other objects will be in part obvious and in part pointed out hereinafter.

The figure in the drawing accompanying this specification is a sectional elevation of a fuel pump equipped with a by-pass valve constructed in accordance with the practice of the invention.

Referring more particularly to the drawing, A designates, in general, a fuel pump comprising a casing B having a bore C for the reception of a guide bushing D wherein is arranged a plunger E.

The pumping chamber F, wherein the plunger E reciprocates, is provided with an enlarged chamber G from which leads a discharge passage H having a conduit J connected thereto through which the fuel pumped by the plunger E may flow to a desired destination, as for instance, to a distributing device of an internal combustion engine.

Arranged between the pumping chamber F and the discharge passage H is a valve guide K which is held fixedly in position by a hollow nut L threaded into the casing B to seat against an end of the valve guide K. A passage O in the valve guide K affords communication between the pumping chamber F

and the discharge passage H and also serves to guide the stem P of a valve Q of the poppet type which cooperates with a seating surface R at the discharge end of the passage O for controlling communication between said passage and the discharge passage H.

A spring S is disposed in the discharge passage H to act with one end against the casing B and with its other end against the valve Q for returning the said valve to its seat R.

On the stem P of the valve Q are the usual guide ribs T between which the fuel pumped by the plunger E may flow to act against the valve Q for opening it.

Within the casing is a supply passage U which may lead from a reservoir (not shown) to the pumping chamber F for conveying liquid fuel thereto. The passage U is provided with an enlarged portion V to accommodate a guide member W having a bore X therein and the discharge end of which terminates in a seating surface Y for a poppet valve Z. The valve Z is normally held closed by a spring b, interposed between the valve Z and the casing B, and has a stem c which extends into the bore X. On the stem c are longitudinally extending ribs d to cooperate with the bore X for guiding the valve.

In its essential respects the pumping device so far described may be substantially like that disclosed in United States Patent No. 1,577,590 granted to G. J. Rathbun, March 23, 1926. The present structure, however, differs from the aforesaid patent in the respect that the valve which controls the supply passage U operates independently of the plunger E, in the present instance the valve Z being unseated by the pressure of the fuel flowing from storage to the pumping chamber F. The plunger E, however, is intended to be actuated in the manner outlined in the patent. It reciprocates continuously so that fuel is alternately drawn into and discharged.

from the pumping chamber F as a continuous operation.

With the plunger E connected to be actuated as in the aforesaid patent its discharge or compression stroke will be of considerably longer duration than the period during which fuel is injected into the engine. In order to nullify a portion of the pumping stroke of the plunger E in excess of that required for charging the engine cylinder means are provided for by-passing a portion of the fuel being pumped. To this end the casing B is provided with a bore e having a threaded outer end f and a reduced portion g to form a shoulder h. The lower end or reduced portion of the bore e in the present instance communicates directly with the inlet passage U through a passage j which opens into the inlet passage u between the valve Z and the source 20 of supply.

Disposed within the bore e is a valve guide k having a flange o, an end surface or shoulder p of which is adapted to seat upon the shoulder h or, as illustrated, upon a gasket q 25 interposed between the flange o and the shoulder h.

Seated upon the opposite or upper end r of the flange o is a packing member s which is suitably compressed against the surface of the bore e by a hollow bushing t which encircles the guide member k and is threaded into the threaded end f of the bore e to hold the guide member k securely in position and to adequately seal the bore e at opposite ends of 30 the flange o.

Extending longitudinally through the guide member k is a bore u for the accommodation of a sleeve valve v having a stem w which extends upwardly through the bore u 40 and carries a head x. A spring y acts with one end against the lower surface of the head x and with its other end against a shoulder z on the exterior of the guide member k.

In the lower portion of the sleeve valve v 45 is a longitudinally extending passage 2 which opens at its lower end into the reduced portion g and communicates with its upper end, through radial passages 3, with an annular groove 4 in the periphery of the valve v. In 50 the guide member k is an annular groove 5 which communicates with the pumping chamber F through a passage 6 in the casing B, and with the bore u through a passage or passages 7 in the guide member k.

The devices whereby the sleeve valve v 55 may be actuated are illustrated as being like those employed in the aforesaid patent. These devices comprise a rod 8 which may be actuated in a well known manner and is connected at its upper end to a lever 9 having a curved surface 10 against which acts a shiftable fulcrum 11 for determining the degree of opening of the sleeve valve v. The 60 lever 9 is also provided with a screw 12

threaded into the end of the lever to act upon the head x for depressing the valve v.

The manner in which the lever 9 and the fulcrum 11 operate to actuate the valve v is well known. It may, however, be pointed out that the fulcrum is intended to be shifted by means of a centrifugal governor, in a manner well understood, so that when the fulcrum is rocked towards the left hand end of the curved surface 10, a position which it 70 will assume when the engine is operating at low speeds, the valve v will be only slightly depressed to establish communication between the annual groove 4 and the passage 7. In such case fuel under pressure will then escape 75 through these channels and through the relief passage 2 into the supply passage U.

Upon acceleration of the engine to which the pumping device is connected the fulcrum 11 will be shifted in the direction of the rod 8 and the valve v will, in consequence be opened to wider limits, thus passing a greater proportion of the fuel from the pumping chamber F to the supply passage U.

In practice the present invention has been 90 found to be unusually efficient. The valve guide k may be adequately sealed against leakage such as commonly occurs in devices of this character. An additional advantage of this form of construction is that the by-pass 95 valve is not constantly subjected to the jars resulting from the thrusts of the plunger E and which are, of course, transmitted by the fuel in the pumping chamber to the elements adjacent thereto.

I claim:

1. In a fuel pump, the combination of a casing having a pumping chamber and supply and discharge passages communicating therewith, valves to control communication between the passages and the chamber, a plunger in the chamber to pump fuel through the discharge passage, a guide member in the casing having a bore and a passage to afford communication between the bore and the pumping chamber, a sleeve valve in the bore having a relief passage in constant communication with the supply passage, and means for actuating the sleeve valve to establish registry between the relief passage and the pumping chamber for bypassing fuel from the pumping chamber to the supply passage.

2. In a fuel pump, the combination of a casing having a pumping chamber and supply and discharge passages communicating therewith, valves controlling communication between the passages and the chamber, a plunger in the pumping chamber to pump fuel through the discharge passage, a bore in the casing and in communication with the pumping chamber, a shoulder in the bore, a guide member in the bore to seat upon the shoulder and having a bore therein and a passage to afford communication between the 120

bore and the pumping chamber, said guide member having a flange seating with one end upon the shoulder, a packing member on the other end of the flange, a sleeve threaded into 5 the casing to compress the packing member between said sleeve and the flange, a spring pressed sleeve valve in the guide member having a relief passage in constant communication with the supply passage, and means for 10 actuating the relief valve to establish communication between the relief passage and the pumping chamber for by-passing fuel from the pumping chamber to the supply passage.

In testimony whereof I have signed this 15 specification.

FRITJOF FRELIN.
